(No Model.)

W. G. ELLIS.

STREET CAR.

No. 398,594.

Patented Feb. 26, 1889.

UNITED STATES PATENT OFFICE.

WILLIAM G. ELLIS, OF AMESBURY, MASSACHUSETTS.

STREET-CAR.

SPECIFICATION forming part of Letters Patent No. 398,594, dated February 26, 1889.

Application filed December 5, 1888. Serial No. 292,753. (No model.)

To all whom it may concern:

Be it known that I, WILLIAM G. ELLIS, a resident of Amesbury, in the county of Essex and State of Massachusetts, have invented certain new and useful Improvements in Street-Cars, of which the following, taken in connection with the accompanying drawings, is a specification.

My invention relates to improvements in street-cars, and the objects of my improvements are, first, to produce a street-car of such construction that it will be lighter and stronger than those built by the present method; second, to simplify the construction and increase the strength and durability of the seats used therein. The first result I attain by the manner of preparing and quality of the prepared material used in the construction thereof, the second by the mechanical devices illustrated in the accompanying drawings, in which—

Figure 1 is an outside elevation of the panel-frame, showing the construction of the parts. Fig. 2 is a view of the post; Fig. 3, an enlarged section on line xx of Fig. 1. Fig. 4 is a back view of the metal guard; and Fig. 5 is a cross-section on yy , Fig. 1.

The post A A, which is the principal support of the body of the seat in open street-cars and Fig. 1, of which there are two to each seat, one at the perpendicular center of each, is secured in the car in the usual manner in such position that it will be at the perpendicular center of the panel-frame B, as shown at A. The panel-frame B is made of wood and consists of three pieces, two uprights, $b b$, and a cross-piece, b' , the interior edges of which are grooved for the reception of a panel if so required, (see Fig. 5,) which are framed together in the usual manner, (shown at b' , Fig. 3,) and are firmly held by the action of the metal guard b^2 and draw-bolts b^4 , as will be explained farther on.

The body of the metal guard b^2 is circular in outline, and its interior is cored out in such proportion that it will pass over, envelop, and fit closely on the top ends of the uprights b , and its center is provided with a hole, s , for the reception of the draw-bolt b^4 . (See s , Fig. 4.) Branching upward from its peripherical surface in the form of a reversed curve is a goose-neck, d , which terminates in a flange, a ,

of such an angle that when all the parts are in position it will fit closely to the flat surface of the post A A, and on its inner surface is a projecting rim, s' , which forms a socket for the reception of the seat-bar s^2 , (shown at s' , Fig. 3,) and terminates in a flange, s^3 , which reaches downward in the proper proportion to become a stiffening-brace to the joints of the panel-frame B.

To secure the parts together, the guard b^2 is placed over the outer top end of the cross-piece b' , one on each end, and the draw-bolt b^4 passed through the hole s , also through the frame-work of the panel-frame B and threaded in the end of the seat-bar s^2 the required distance to press the joints of the panel-frame B closely together, also to draw and secure the seat-bar s^2 firmly in the socket s' , as shown at b^4 and s' , Fig. 3. The flanges a are then secured to the front and rear surfaces of the post A A by a screw-bolt, a^3 , Fig. 1, the curved goose-necks d forming the grab-rails of the seat, thus securing with three bolts the panel-frame B, grab-rail d , and seat-bars s^2 .

It will be noted that in this mode of construction the metal guard, grab-rail d , seat-bar socket s' , and strengthening-brace s^3 are all combined in one piece.

The front and rear surfaces of the post A A are parallel and in straight line, as shown at A A, Fig. 1. Its outer and inner surfaces are parallel with each other in the form of a reversed curve, as shown at A A, Fig. 2, and the present manner of making them is to cut them to the desired shape from a straight plank of the required thickness, thus cutting across the grain of the wood, as shown at s^4 , Fig. 2, which reduces its strength at the place where it is most needed, and as the uprights $b b$ are first cut to the shape shown at b , Fig. 1, and the side surfaces are again cut the same curve of the post A A, the evil is intensified. The manner in which I remedy this defect, and which forms part of the subject-matter of this application for Letters Patent, is as follows: I prepare the material for the posts A A and uprights $b b$ in straight parallel pieces of the required dimensions. Then by the use of steam or other suitable means bend and set them to and in the required form, when the grain or fiber of the wood, running in the same

direction with the curves, as shown by the arrows on the post A A, Fig. 2, makes them of equal strength at all points.

It will be understood that I do not claim 5 the posts A A as exclusive of posts in street-cars, but simply as of improved construction, as before explained, the improvement consisting of bringing the fiber or grain of the wood in line with the curves in the posts A A, and 10 thereby increasing the relative reactive and shearing tenacity of said curves and ultimate strength of said post in the proportion of ten to one at the lowest ratio, for which reason it is a valuable improvement in the construction 15 of said cars, and, furthermore, from the fact that the post being of equal strength in all parts it can be made lighter and possess more strength than those at present used, which have to be made much stouter than is wanted 20 in order to insure the required strength to the parts that are cut across the grain, while in the event of accident or collision it will be seen that a blow that would shatter a post the fiber of which has been cut across would not 25 affect—certainly would not destroy—a post of which the fiber is not injured. For this reason its use would enable the manufacturer to build a lighter car having more proportionate strength and safety than can be attained by 30 the present mode. As this improvement originated with and has been practically adapted and applied by me in the construction of street-cars that I am now building, I feel justified in claiming the exclusive use thereof in the manufacture of street-cars. I do not claim the 35 panel-frame B as exclusive of panels, but sim-

ply as of new and improved construction, inasmuch as its component parts are constructed in the manner before explained, and for that reason possess the same reliable qualities as 40 the posts A A, the new and original device being the metal guard b², which combines in itself the quadruple functions before named.

Having thus described and defined my invention, what I claim as new, and desire to 45 secure by Letters Patent, is—

1. As an improvement in street-cars, the within-described post A A, the uprights b b, and cross-piece b' of the panel-frame B, constructed and adapted as herein described, for 50 the purposes set forth.

2. In the panel-frame B of a street-car, the metal guard b², having the goose-neck d, with the flange a, rim-socket s', hole s, and flange s³, constructed substantially as herein described, for the purposes set forth. 55

3. In a seat for street-cars, the panel-frame B, with the metal guard b², having the goose-neck d, with the flange a, the hole s, rim-socket s', and flange s³, in combination with the 60 post A A, seat-bars s², draw-bolts b⁴ and a', and foot-rail stanchion c, constructed and arranged as herein described, for the purposes set forth.

In testimony whereof I have signed my name to this specification, in the presence of two 65 subscribing witnesses, on this 20th day of November, A. D. 1888.

WILLIAM G. ELLIS.
